UNITED STATES PATENT OFFICE

DANIEL K. RICE, OF POLO, ILLINOIS

WHEELED TOY VEHICLE

Application filed February 17, 1928. Serial No. 255,055.

The present invention relates to a toy vehicle movable on the wheels and has for its prime object to provide a vehicle of this nature simulating an aeroplane and having 5 controls for steering purposes similar to an aeroplane.

Another very important object of the invention resides in the provision of a three wheeled vehicle of this nature having a body 10 in simulation of an aeroplane fuselage with a rudder at the rear end thereof and a propeller at the front end thereof and steering means for rotating the propeller and front wheel simultaneously and means for steering 15 the rear wheel and rudder simultaneously.

A still further very important object of the invention resides in the provision of a toy vehicle of this nature which will afford considerable helpful and pleasing amusement 20 to the young.

A further object of the invention resides in the provision of a vehicle of this nature which is simple in its construction, strong and durable, inexpensive to manufacture, 25 easy to run and control, thoroughly efficient and reliable in operation, and otherwise well adapted to the purpose for which it is designed.

With the above and numerous other objects 30 in view as will appear as the description proceeds, the invention resides in certain novel features of construction, and in the combination and arrangement of parts as will be hereinafter more fully described and claimed.

In the drawings:

Figure 1 is a side elevation of the vehicle embodying the features of my invention showing the rear portion in vertical section,

Figure 2 is a vertical longitudinal section 40 through the forward portion of the vehicle,

Figure 3 is a fragmentary bottom plan view showing particularly the forward portion of the vehicle,

Figure 4 is a vertical transverse section

taken substantially on the line 4—4 of Figure 3,

Figure 5 is an enlarged detail section taken substantially on the line 5—5 of Figure 3,

Figure 6 is a fragmentary top plan view 50 of the vehicle, and

Figure 7 is a bottom plan view of the rear portion of the vehicle.

Referring to the drawings in detail it will be seen that the numeral 5 denotes the body 55 of the vehicle which is shaped in simulation of the fuselage of an aeroplane and has wings 6 projecting laterally from the sides thereof outwardly in simulation of the wings of an aeroplane. The fuselage like body 5 has a 60 seat 7 in the central portion thereof accessible from an opening 8 in the top thereof simulating the cockpit of an aeroplane. A pair of longitudinally extending bottom boards 9 and 10 have adjacent ends spaced and spanned 65 by a pair of angle iron bars 11 disposed in spaced parallel relationship longitudinally of the fuselage body. V-shaped brackets 12 are secured at their upper ends to side members 13 in the fuselage and extend down below 70 the vehicle body and have journaled at their apices a shaft 14 on the outer end of which are wheels 15 and on the intermediate portion adjacent the center a sprocket 16. A shaft 17 is journaled in brackets 18 rising from the 75 intermediate portion of the bars 11 and has at its ends cranks 19 oppositely disposed as to direction and having on their extremities pedals 20. On this shaft 17 there is mounted a sprocket 21 preferably larger in diameter 80 than the sprocket 16 and a chain 22 is trained over the sprockets.

Also on the shaft 17 is a pulley 23. A shaft 24 is journaled through the front of 85 the fuselage like body 5 and in a cross member 25 between the side members 13 and 26 has a pulley on the intermediate portion thereof as indicated at 26. A cable 27 is trained over the pulleys 26 and 23 and also 90

over an idler pulley 28 mounted in a bracket 29 rising from the board 9.

It will thus be seen that when the shaft 17 is rotated by the crank pedal the wheels 15 rotate to move the vehicle and simultaneously the propeller 30 on the front end of the shaft 24 is rotated in simulation to the propeller of an aeroplane.

A shaft 31 is journaled vertically in the rear wall of the fuselage like body 5 and terminates below the body in a fork 33 in which is journaled the rear wheel 34. The bracket 35 from the upper end of the shaft 31 supports a rudder and elevator simulating device 36 at the rear of the body 5. The shaft 31 is provided with a sprocket 37 over which is trained a chain 38. A block or the like 39 rises from an intermediate portion of the bottom board 10 to the rear of the seat 7 and has rockable thereon in a horizontal plane a bar 40 which may be pivoted as at 41 intermediate its ends. Rods 42 are attached to the ends of the chain 38 and are attached to the ends of the bar 40 by means of turn buckles 43 and links 44. A rod 45 is attached to the bar 40 adjacent one end thereof and is bent intermediate its ends so as to extend forwardly and is attached pivotally to an intermediate portion of a lever or control stick 46 as is indicated at 47. This lever 46 is pivoted at its lower end as at 48 on the forward portion of the board 10. Obviously by rocking the control stick 46 forwardly and rearwardly the bar 40 is swung so as to pull or push on the rod 42 and cause the chain 38 to rock the sprocket 37 thereby rocking the shaft 31 to steer the wheel 34 and at the same time turn the device 36. As is shown to advantage in Figure 5 the shaft 17, the sprocket 21 and the pulley 23 may be fastened integrally and the shaft is journaled in ball bearings 50 at the upper ends of brackets 18.

The body 5 may be made of sheet metal using the bottom boards 9 and 10 and the side members 13 as the frame structure in conjunction with the front wall 51 and rear wall 52. The wings 6 may be riveted or otherwise securely attached to the sides of the body.

From the above detailed description it is thought that the construction, operation, utility and advantages of the invention will be understood.

It is preferable to provide springs 53 attached to the ends of the bar 40 and extending forwardly and attached to the back 54 of the seat 7, these springs tending to hold the bar in the position shown in Figure 7 so that the vehicle will move straight ahead until the stick is actuated and the springs will return the parts to a straight ahead position whenever the stick is released.

The present embodiment of the invention

has been disclosed in detail merely by way of example since in actual practice it attains the features of advantage enumerated as desirable in the statement of the invention and the above description.

It will be understood, however, that changes in the details of construction, and in the combination and arrangement of parts may be resorted to without departing from the spirit or scope of the invention as hereinafter claimed or sacrificing any of its advantages.

Having thus described my invention, what I claim as new is:

1. A riding toy in the form of an aeroplane comprising a fuselage-like body, wings projecting laterally and outwardly from the sides of the body, a pair of side members in the body, a cross member between the side members, a shaft journaled longitudinally in the forward portion of the body, and in the cross member, a propeller on the front end of the shaft in front of the body, a pair of brackets, one depending from each side member said brackets being V-shaped in formation, a shaft journaled in the apices of the brackets, wheels on the last mentioned shaft, a sprocket on the last mentioned shaft, a pair of longitudinal bottom boards in the body having adjacent ends spaced, a pair of bars disposed between said adjacent ends of the bottom boards in spaced relation to each other, a third shaft, means for journaling the third shaft on the bars, foot actuated means for rotating the third mentioned shaft, a sprocket on the third mentioned shaft, a chain trained over said sprockets, a pulley on the third mentioned shaft, a pulley on the first mentioned shaft, an idler pulley on the forward portion of one of the bottom boards, and an endless cable trained over the pulley.

2. A riding toy of the class described in the form of an aeroplane comprising a fuselage-like body, wings projecting laterally and outwardly from the sides of the body, a pair of side members in the body, a cross member between the side members, a shaft journaled longitudinally in the forward portion of the body and in the cross member, a propeller on the front end of the shaft in front of the body, a pair of brackets, one depending from each side member, said brackets being V-shaped in formation, a shaft journaled in the apices of the brackets, wheels on the last mentioned shaft, a sprocket on the last mentioned shaft, a pair of longitudinal bottom boards in the body having adjacent ends spaced, a pair of bars disposed between said adjacent ends of the bottom boards in spaced relation to each other, a third shaft, means for journaling the third shaft on the bars, foot actuated means for rotating the third mentioned shaft, a sprocket on the third mentioned shaft, a chain trained over said sprocket.

ets, a pulley on the third mentioned shaft, a pulley on the first mentioned shaft, an idler pulley on the forward portion of one of the bottom boards, and an endless cable trained over the pulley, a vertical shaft journaled in the rear of the body and having a fork at the lower end thereof, a wheel journaled in the fork, a sprocket on the vertical shaft, a rudder structure on the vertical shaft, a chain trained over the sprocket on the vertical shaft, rods connected to the ends of the chain, a rocker body with which the rods are engaged, spring means holding the rocker in a predetermined position, and means for actuating the rocker for steering purposes.

In testimony whereof I affix my signature.
DANIEL K. RICE.
